VALVE STEM CAP

William Martino, Detroit, Mich.

Application February 6, 1939, Serial No. 254,976

2 Claims. (Cl. 138—89.3)

My invention relates to inflating valves of the type employed in pneumatic tires, and has among its objects and advantages the provision of an improved valve stem cap.

5 In the accompanying drawing:

Figure 1 is an elevational view of a valve stem and a sectional view of a cap therefor in accordance with my invention;

Figure 2 is a sectional view along the line 2—2 10 of Figure 1;

Figure 3 is a sectional view of the cap detached from the valve stem; and

Figure 4 is a top plan view of the cap.

In the embodiment selected to illustrate my invention, I make use of a valve stem 10 which may be conventional in all respects with the exception that I omit threads at the end 12. In lieu of threads, I provide a plurality of projections 14, which projections have sharp edges 16 and curved faces 18 tangentially arranged with respect to the circumference of the stem. When viewed according to Figure 2, the projections 14 take the configuration of wedge-shaped teeth all projecting in the same direction.

25 Cap 20 is formed of material such as rubber of semi-rigid properties having a hexagonal configuration when viewed according to Figure 4. The cap is provided with a bore 22 which tapers downwardly when viewed according to Figure 3.

30 Bore 22 at its end 24 fits tightly about the stem reach 26. Inside the bore 22 I position a soft rubber cushion 28 arranged to engage the end 30 of the valve stem for effecting a dust-tight seal.

35 Figure 1 illustrates the cap 20 in position, at which time the cushion 28 is pressed firmly against the end 30 and the lower end of the cap closely embracing the run 26. In operation, the cap 20 is applied by exerting downward pressure 40 and rotating the cap in a clockwise direction when viewing Figure 2 when pushing the cap

home. The cap will rotate easily because of the curved faces 18 on the projections 14, but the projections will project partly into the material of the cap so as to effectively support the same against accidental displacement, with the cushion 24 effectively pressed between the top of the cap and the end 30.

Cap 20 may be removed by exerting a pull and rotating the cap in a clockwise direction. My invention permits the cap to be quickly and easily attached to or detached from the valve stem. It eliminates the tedious and time consuming manipulation peculiar to dust caps of the threaded type. The tapered configuration of the bore 22 renders the cap applicable to modern 15 valve stems of the modern type.

Without further elaboration, the foregoing will so fully illustrate my invention that others may, by applying current knowledge, readily adapt the same for use under various conditions of service. 20

I claim:

1. The combination of a valve stem having a projection extending laterally of its outer face adjacent one end of the stem, said projection having a sharp edge and a face tangentially arranged 25 with respect to said outer face of the stem, and a cap of resilient material adapted to be pressed onto said one end of the valve stem, with said projection extending into the material of the cap.

2. The combination of a valve stem having a 30 plurality of projections extending laterally from its outer face adjacent one end of the stem, said projections having sharp edges and faces tangentially arranged with respect to said outer face of the stem, a cap of resilient material having an 35 opening for insertably receiving said one end of the valve stem, the opening in said cap being tapered to sealingly embrace the stem beyond said projections.

WILLIAM MARTINO. 40
